KNIFE

Robert S. Cathey, Portland, Oreg.

Application October 5, 1935, Serial No. 43,736

3 Claims.

(Cl. 30—9)

This invention relates generally to cutlery and particularly to an improved form of paring knife.

The main object of this invention is the construction of an improved form of paring knife which will facilitate the paring operation by curving the cutting edge to conform generally with the contour of a rounded object and to place the cutting edge approximately on a line with the back edge of the knife handle at which line the force of the hand is applied.

The second object is to so construct the knife that notwithstanding the curved cutting edge, there will be a uniform increase in the flexibility of the blade from the handle toward the point of the blade.

The third object is to so construct the knife that the advantages of the pointed blade are not lost.

These, and other objects, will become more apparent from the specification following as illustrated in the accompanying drawing, in which:

Fig. 1 is a side elevation of the knife.

Fig. 2 is an edge elevation thereof.

Fig. 3 is a section taken along the line 3—3 in Fig. 1.

Fig. 4 is a section taken along the line 4—4 in Fig. 1.

Fig. 5 is a section taken along the line 5—5 in Fig. 1.

Fig. 6 is an elevation of the knife taken from the point end.

Similar numbers of reference refer to similar parts throughout the several views.

Referring in detail to the drawing, there is shown a handle 10 from which projects a blade 11 whose cutting edge 12 is curved so that the middle portion 13 is approximately in a line with the rear side 14 of the handle 10. The tip 15 is preferably pointed as shown and the rear edge 16 of the blade 11 is substantially parallel with the cutting edge 12, although the blade 11 tapers gradually from the handle 10 to the tip 15.

It will be noted that the portion 17 of the cutting edge 12 is curved in a reverse manner to the middle portion 13. While the middle portion 13 of the cutting edge 12 has been shown substantially in alignment with the edge 14, it is

obvious that it could be placed on either side of this line without departing from the spirit of this invention, although it is desirable to have the actual cutting edge close to the line of the rear side 14 as it facilitates the guiding of the 5 blade along the inside of the peel.

In some instances, it may be desirable to reduce the width of the blade 11 along the section 4—4, although it is desirable to retain as much material at this point as is possible to offset the 10 wear caused by sharpening.

I am aware that various forms of paring knives have been constructed in the past and that knives have been constructed with curved cutting edges. I therefore do not intend to cover this 15 device broadly but limit myself to the forms particularly set forth in the accompanying claims.

I claim:

1. A paring knife having a blade which tapers 20 in thickness toward its point and having its cutting edge in the form of a reversed curve with a concave portion near the middle thereof and a convex portion toward the point, the middle of the concave portion and the point of the knife 25 being substantially in alignment with the rear edge of the knife handle.

2. A paring knife having a blade which tapers in thickness toward its point and having a concavely curved cutting edge extending approximately to the line of the rear edge of the knife 30 handle and having the rear edge of the blade substantially in parallelism with the cutting edge thereof and having the rear edge and cutting edge converging to form a point, said point being 35 also in alignment with the rear edge of the handle.

3. A paring knife having a backwardly curved blade tapering to its point and having the cutting edge thereof in the form of a reverse curve, 40 the concave portion of which extends across the major portion of the blade length and the convex portion extending along the tip of the blade, the middle of the concave portion and the tip of the convex portion of the blade being substantially 45 in alignment with the rear end of the knife handle.

ROBERT S. CATHEY.
